UNITED STATES PATENT OFFICE.

WILLIAM M. NECKERMAN, OF YOUNGSTOWN, OHIO.

TAPPING AND REAMING HEAD.

1,080,119.

Specification of Letters Patent.

Patented Dec. 2, 1913.

Application filed November 25, 1912. Serial No. 733,246.

To all whom it may concern:

Be it known that I, WILLIAM M. NECKERMAN, a citizen of the United States, residing at Youngstown, in the county of Mahoning and State of Ohio, have invented new and useful Improvements in Tapping and Reaming Heads, of which the following is a specification.

My invention relates to heads for tapping and reaming and has been devised especially for tapping and reaming pipe-couplings, but it is not limited to this purpose.

It is the object of my invention to provide heads for tapping, or reaming, or both, which can be attached to the spindle arranged and constructed to rotate the heads axially and feed them longitudinally; and to provide novel means for projecting and retracting the threading dies, and for adjusting these dies for variations in the diameters of the coupling-blanks.

My invention also includes a novel form of carrier for the reaming tools and the threading dies and novel means for controlling the movements of the dies whereby they may be securely locked during the threading operation and may be readily released and retracted at the close of this operation. Other objects will appear in the 20 description.

Referring to the accompanying drawings, Figure 1 is a central longitudinal section of a threading and reaming head embodying my invention; Fig. 2, a horizontal section 25 on the line II—II, Fig. 1; Fig. 3, a horizontal section on the line III—III, Fig. 1; Fig. 4, a side view of a portion of the head; Fig. 5, a side elevation, showing a development of a portion of the rings for operating 30 the threading dies and for locking and releasing the same; Fig. 6, a side elevation of the upper ring shown in Fig. 5; Fig. 7, a cross-section on the line VII—VII, Fig. 1; and Fig. 8, an elevation of two co-operating 35 heads, together with connected and co-operating parts, portions being in section.

On the drawings, 1 designates the frame of the threading and reaming head having in its lower or free end a series of radial 40 slots 2 extending upwardly to the line 3 and from the exterior of the frame to the central opening 4, which extends downwardly to the bottom of the frame. The opening 4 has the contracted upward extension 5, 45 and the still more contracted extension 6 immediately above the extension 5. The

slots 2 have upward extensions 7 communicating with the opening 4. The said extensions have equal heights, corresponding to the up and down travel of the cone-shaped 60 adjusting head 8, which has the main portion of its body lying in the opening 4 and its upper contracted portion 9 extending through the extension 5 and into the extension 6, which latter extension guides the 65 said extension 9.

The head 8 is provided at its sides with the radial guide-ribs 10 having their upper ends guided in the extension slots 7 and their lower ends preferably spaced slightly 70 from the plane of the bottom of the head 1 so as to leave the space 11. The ribs 10 are inclined inwardly and downwardly and have each an open guide-slot 12 extending along one side thereof parallel with the 75 outer face of the rib containing the associated guide-slot. 13 are the threading dies fitting the radial slots 2 and having the external thread-cutting teeth 14. The top of the dies 13 are guided horizontally by the 80 walls on the said line 3 and their bottoms are flush with the bottom of the head 1. The inner edge of the dies 13 are inclined so as to fit the outer faces of the ribs 10 and have inclined hook-like flanges 15 fitting the slots 85 12 in the ribs.

The head 8 has between the main body thereof and the extension 9 the threaded portion 16 on which the adjusting nut 17 works, the nut lying in the opening 4. It 90 is provided with a series of radial holes 18 to receive the handle 19 which extends out through the slot 20 or 21 beyond the outer face of the head 1, as shown in Fig. 3.

The collar 22 surrounds the extension 9 95 and has a larger portion engaging the top of the nut 17 and spaced from the top of the opening 4 by a distance equal to the height of the extensions 5 and 6. The upper contracted portion of the collar 22 is 100 adapted to enter the extension 5.

The radial bar 23 lies in notches in the top of the collar 22 and has its reduced ends lying in notches 27, in the bottom of the rotary ring 24 fitted about a reduced portion 25 of the head, having the radial slot 26 to permit the bar 23 to travel up and down with the head 8.

The ring 28 lies above the ring 24 and in alinement therewith, and rotates on the 110 portion 25 of the head 1. The upper end of the ring 28 bears against the bottom of

the ring 29 secured rigidly to the portion 25 by screws 30, one only being shown. Above the portion 25 is the reduced tapered lug 31 having the cross-opening 32, the lug fitting in the end of the spindle 33, by which the entire head is supported, rotated and reciprocated in a manner well known. The cross-pin 34 extends through the opening 32 and into the spindle 33.

10 The bottom of the head 8 has a central opening, containing the coiled expansion spring 35, compressed between the top wall of the opening and the boss extending into the opening from the cover plate 36 which 15 is secured by the bolts 37 to the bottom of the head 1 and forms a bottom guide for the dies 13. The screw 38 works in the plate 35 and engages a plate 39 on which the lower end of the spring rests. By turning the screw 38 the tension of the spring 20 may be adjusted.

The upper edge of the ring 24 has several teeth 40 having their left-hand walls 41 perpendicular to the ring and the right-hand wall 42 inclined to the bottom of the next tooth. The apex of each tooth is beveled at the angle of 45° with the right-hand wall of the tooth.

30 The bottom edge of the ring 28 has the same number of teeth 40 as the ring 24, the right-hand wall 41 of each tooth being perpendicular to the ring 24 and the left-hand wall 42 being inclined to the base of the next tooth, the inclination of the wall 42 of the 35 two rings being parallel, or having the same angle with regard to the wall 41. The apex of the tooth 40 of the ring 28 is also beveled at the angle of 45° with the wall 41 of the ring 28.

40 When the tool-head is ready for work the parts are as shown in Figs. 1 and 5, the two beveled portions *a* of adjacent teeth on the two rings 24 and 28 being in engagement as shown on Fig. 5. The spring 39 tends to 45 push the ring 24 upwardly and would push the same upwardly if there were no means for preventing the rotation of the ring 28, because, if the ring 28 were free to rotate the beveled portions *a* on the teeth 40 would 50 wedge or cam the ring 28 to the left until the walls 41 of the said teeth came into alinement, whereupon the spring 39 would push up the head 8, the ring 17, the collar 22, the bar 23 and the ring 24 until the 55 teeth 40 on the rings 24 and 28 interfit and the lower walls 42 engage the upper walls 42. By the movement of the head 8 upwardly the dies 13 were caused to move inwardly as is required at the close of a 60 threading operation to permit the tool-head to be withdrawn from the hole threaded thereby.

The ring 28 has the handle 43 by which it may be turned. If the ring 28 be turned 65 to the left, the contacting wall 42 will force

the lower ring 24, the bar 23, the collar 22, the ring 17, and the head 8 downwardly, thereby causing the dies 13 to be projected to their working position, at which time the surfaces *a* of co-acting teeth will engage 70 each other, further movement of the ring to the left after the surfaces *a* engage being prevented by the dog 44. This dog has radial movement in the tube or casing 45 inserted in the opening 46 in the ring 28. A 75 spring 47 presses the dog inwardly and has its outer end restrained by the cap 48 on the casing 45. The spring surrounds the stem 49 attached to the outer end of the dog and extending through the cap 48. The bell-crank 50 has its angle pivoted to the arm 51 on the cap 48 and its inner arm pivoted to the stem 49. The outer arm of the lever 50 is provided with a roller 52 which may engage with a fixed projection 52' to cause the outer arm to be raised and the dog to be withdrawn from engagement with the radial wall of one of the notches 53, when the threading dies have entered the coupling-blank 53² the desired depth.

The outer end of the bell-crank 50 may be raised by hand, if desired, to withdraw the dog 44. When the beveled portions *a* coincide, the dog 44 has reached the radial or stopping end of one of the notches 53 in the 90 periphery of the portion 25 of the frame 1, so that the pressure of the spring 35 cannot rotate the ring to the left to permit the teeth 40 to interlock with their walls 42 in engagement with each other.

The periphery of the frame 1 somewhat above the bottom thereof is provided with radial slots 54 open at their outer sides and top ends. In these slots 54 are the reamers 55 having their lower ends beveled inwardly 105 toward the bottom of the slots as at 57, their intermediate portions 58 parallel with the axis of the head, and their upper ends provided with the radial projections 56 which engage the edge of the coupling-blank 53² 110 at the end of the threading operation. The dies 13 thread the coupling-blank from its ends inwardly to predetermined depths fixed by the action of the lever 50 or the projections 56. The portions 57 and 58 of the 115 reaming cutters cut away the threads made by the dies 13 making the interiors at the ends of the pipe-couplings smooth and somewhat larger than the threaded portion of the coupling, thereby giving the interior of the 12 finished coupling its usual shape. The cutters 55 are clamped in place by the ring 59, which rests on their upper ends, the ring being spaced from the frame beneath it to permit the ring to bear on the cutters after their 12 lower ends have been ground off to compensate for the grinding away of the beveled portions 57 for sharpening the cutters.

The radial position of the dies 13 may be adjusted by rotating the nut 17 by means of 13

the handle 19, but the handle 19 can be turned only when the head 8 is in its upper position, because the slots 20 and 21 are connected at their upper ends and not at 5 their lower ends (Fig. 4). When the head 8 moves up in the opening 4, the handle 19 moves up in the slot 20 or 21. When the handle reaches the top of its slot, it may be moved across to the top of the other slot, if 10 this movement will give the desired adjustment of the head 8, and the handle can be taken out of the top of the latter slot, and placed in another hole 18 at the top of the other slot, and the nut turned still farther, 15 if the first movement of the handle was not sufficient. The holes 18 are spaced so that consecutive holes 18 can register at the same time with the slots 20 and 21, so that the handle can be removed from one slot and 20 hole 18, and placed in the adjacent slot and hole. The nut 17 can be successively moved by changing the handle to successive holes and moving it across from one slot to the other, so as to obtain the desired adjustments of the head 8 and consequently, of 25 the dies 13. The space 11 permits the head to be adjusted downwardly.

Fig. 8 shows the coupling-blank 53² threaded and reamed at its lower end by the lower 30 head. By retracting the lower head the upper head can be lowered to thread and ream the upper end of the blank. The heads have the telescopic projections 36' and 36² to keep the heads in alignment, and 35 are covered by my application, Seria. Number 733,245 filed November 25, 1912.

I claim—

1. In a tap, a frame, threading dies having radial movement therein, a head having 40 longitudinal movement on the frame and connected to the inner edges of the dies so as to move the dies radially as the head moves longitudinally, a spring in the head exerting a pressure tending to move the dies radially, coöperating rings, each provided with a plurality of opposing cam teeth, one ring being movable on the other for moving the head against the action of the spring, and means for releasably locking 45 the movable cam when the dies have been projected thereby to their working positions.

2. In a tap, a frame, threading dies having radial movement therein, a head having 55 longitudinal movement on the frame and connected to the inner edges of the dies so as to move the dies radially as the head moves longitudinally, a spring in the head exerting a pressure tending to move the dies 60 radially, and coöperating toothed cam rings rotatable transversely of the head, one cam ring being movable on the other for moving the head against the action of the spring, the said spring having one end reacting 65 against the front end of the frame.

3. In a tap, a frame, radially movable threading dies carried thereby, a head for moving the dies radially, a spring tending to retract the dies, a fixed cam and a movable cam coöperating therewith and with the head to operate the head in opposition to the spring, the cams having inclined surfaces arranged to hold the dies in working position and tending under the action of the spring to move the movable cam to a 75 position to release the head from the holding action of the inclined surfaces, and means for releasably locking the movable cam when the said inclined surfaces are coöperating to hold the dies in working position. 80

4. In a tap, a frame, radially-movable threading dies therein, a head movable at an angle to the movement of the dies, a nut adjustable longitudinally on the head, a spring tending to force the head in a direction to cause a retraction of the dies, and means bearing on the nut and acting to hold the dies in threading position against the force of the spring. 85

5. In a tap, a frame, radially-movable threading dies therein, a head movable at an angle to the movement of the dies, a nut adjustable longitudinally on the head, a spring tending to force the head in a direction to cause a retraction of the dies, means bearing on the nut and acting to hold the dies in threading position against the force of the spring, and means preventing the 90 rotating of the nut when the dies are in 100 threading position. 95

6. In a tap, a frame, radially-movable threading dies therein, a head movable at an angle to the movement of the dies, a nut adjustable longitudinally on the head, 105 a spring tending to force the head in a direction to cause a retraction of the dies, means bearing on the nut and acting to hold the dies in threading position against the force of the spring, and a handle for the nut extending outwardly from the frame and movable in a longitudinal slot in the frame and in a transverse slot therein communicating with the longitudinal slot, the handle being at the closed end of the longitudinal slot when the dies are in threading 115 position and in line with the transverse slot when the dies are retracted.

7. In a tap, a frame having a U-shaped lateral slot with the legs thereof extending 120 toward the free end thereof, a head movable longitudinally of the frame, threading dies operatively connected to the head, means including a nut adjustable on the head, for holding the head with the dies in their 125 working position, the nut having in its periphery a series of holes spaced apart to correspond with the distance between the legs of the U-shaped slot, and a handle in one of the holes in the nut, and at the closed 130

end of one of the legs of the slot when the dies are retracted and in line with the transverse member of the slot when the dies are retracted.

8. In a tap, a rotatable frame having an axial opening, radial slots communicating therewith, and a transverse slot, threading dies in the radial slots, a longitudinally movable head in the axial opening to actuate the dies and hold them in their threading positions, a collar carried by the head, a cross-bar reciprocable longitudinally of the frame and in the transverse slot, a ring around the frame and on the ends of the bar, the ring having inclined teeth on its edge opposite the bar, a rotary ring having inclined teeth fitting the teeth on the other ring, a spring pressing the first ring toward the second ring, the apices of the teeth having contacting surfaces inclined transversely of the inclination of the teeth, whereby the spring tends to rotate the second ring so that its teeth may pass the teeth on the first,

and permit under the action of the spring the teeth to move into intermeshing engagement and the dies to be retracted, a dog cooperating with the notches in the frame to prevent the rotation of the second ring, and means for withdrawing the dog from any notch in which it may rest. 25

9. In a tapping and reaming device, a rotary frame, a series of radially arranged threading dies therein, a series of radially arranged and longitudinally disposed reaming cutters having the ends nearest the dies supported on transverse walls in the frame, a clamping ring resting on the other ends of the cutters, and means for drawing the ring against the last-named ends of the cutters and toward the said transverse walls. 30 35

Signed at Youngstown, Ohio, this 21st day of November 1912.
